UNITED STATES PATENT OFFICE.

FRANK GODWARD, OF BERGHLZ, OHIO.

RAILROAD-TIE.

961,294.

Specification of Letters Patent. Patented June 14, 1910.

Application filed September 17, 1909. Serial No. 518,204.

To all whom it may concern:

Be it known that I, FRANK GODWARD, a citizen of the United States, residing at Bergholz, in the county of Jefferson and 5 State of Ohio, have invented certain new and useful Improvements in Railroad-Ties, of which the following is a specification.

This invention relates to certain new and useful improvements in railroad ties.

10 The object of my invention is to provide a metallic guard plate for a tie, so constructed as to prolong the life of the tie, providing a durable means for holding the rails to the ties, and a readily adjustable securing mechanism whereby the rails may be readily removed or secured.

With these and other objects in view, the present invention consists in the combination and arrangement of parts as will be 20 hereinafter more fully described and particularly pointed out in the appended claim, it being understood that changes in the specific structure shown and described may be made within the scope of the claim without departing from the spirit of the invention.

In the drawings forming a part of this specification, and in which like numerals of reference indicate similar parts in the several views, Figure 1 is an elevational view 30 showing my device as secured to an ordinary wooden railroad tie, Fig. 2 is a top view thereof.

This invention has special reference to 35 that class of ties in connection with which a metallic bearing plate is employed to offer a firm base for the rails, as well as to provide a durable securing means for fastening the rails to the ties.

40 In the accompanying drawings, the numeral 5 designates an ordinary wooden tie, which above is reinforced by means of the preferably steel base plate 6, which has its opposite ends 7 recurved and extending 45 obliquely upward a distance sufficient to insure the beveled edge 8 of the end to come in contact with the web 9 of the rail 10, the base of which is held below this securing flange 7. The recurved flange 7 is provided 50 with a rectangular incision 12, the metal between the incision being stamped outward

and downward to form the spur lip 15 having the beveled edge 16, this lip being driven into the tie, to prevent any lengthwise displacement of the same. These terminal spur 55 lips are centrally positioned and perform the functions of spikes as it were, in assisting to hold the base plates to the ties.

Each base plate proximal to its end flange has two spike openings marked 20, all of 60 these spike openings being in alinement, as shown in the top view.

In connection with each base plate, I employ two securing plates 22, each having an upwardly directed stop flange 23, each 65 ending in an oblique edge arranged to contact with the flange 9 of the rail as shown. Each securing plate has two spike openings marked 24 in the drawings arranged for co-action with the spike openings within the 70 base plate, so that the spikes 25 may be carried through the openings 20 and 24 and be driven into the tie to firmly hold the securing plates 22 to the base plate, and the base plate in turn to the tie 5.

In the use of the device, it is found necessary to remove but one of the spikes 25 in case the rail should be removed. In the operation of removing a rail, the operator would remove one of the spikes, the remaining spike serving as a pivot. The securing plate having been carried outward, the rail is removed or secured as the case may be, when the securing plate is again forced into position and secured by means of a spike. 85

The metallic base plate above described may be formed entire at one operation, being stamped from sheet metal as stated. So also can the securing plate be formed entire at one operation. This attachment may 90 be effected in any suitable workmanlike manner and the base plate can of course also be used in connection with concrete or metallic ties, a bolt being used to secure the plate to the base member. 95

The device is simple and inexpensive in construction, and both durable and efficient in operation.

What is claimed is:

In combination, a wooden tie, a metallic 100 base plate having its opposite ends recurved to form securing flanges, a part of each

flange being incised to form a bevel edge terminal centrally positioned spur lip, said plate proximal to its end flanges having two spike openings and two securing plates having upwardly directed stop flanges and two alining openings, all of said openings being in alinement, and securing spikes passing through said openings to hold said securing

plates to said base plate and said base plate to said tie, as and in the manner set forth. 10

In testimony whereof I affix my signature, in presence of two witnesses.

FRANK GODWARD.
